CENTER BEAM FOR A RAILWAY VEHICLE

Kenneth J. Austgen, Griffith, Ind., assignor to Pullman
Incorporated, a corporation of Delaware

Filed Nov. 15, 1961, Ser. No. 67,520

Term of patent 14 years

(Cl. D66—3)

FIGURE 1 is a perspective view of the center beam of a railway vehicle showing my new design;

FIGS. 2, 3 and 4 are cross-sectional views taken respectively on the lines 2—2, 3—3 and 4—4 of FIG. 1, each on a relatively enlarged scale; and

FIG. 5 is a side elevational view, on a smaller scale.

The side and end of the center beam not shown in the drawing are substantially the same as those shown.

I claim:

The ornamental design for a center beam for a railway vehicle, substantially as shown and described.
